76-589

EX

OP D 16,184

DESIGN.

—o—
A. PETZOLD.

RUG.

№. 16,184.

Patented July 28, 1885.

UNITED STATES PATENT OFFICE.

ADOLPH PETZOLD, OF PHILADELPHIA, PENNSYLVANIA.

DESIGN FOR A RUG.

SPECIFICATION forming part of Design No. 16,184, dated July 28, 1885.

Application filed April 11, 1885. Term of patent 14 years.

To all whom it may concern:

Be it known that I, ADOLPH PETZOLD, a citizen of the United States, and a resident of Philadelphia, Pennsylvania, have invented and produced a new and original Design for a Rug, of which the following is a specification, reference being had to the accompanying photographic illustration, to which reference is made.

The accompanying illustration represents one half of my rug, the other half being a duplicate of that shown, excepting that the position of the line in the end panel of the half not shown is reversed, (looking to the left,) so as to face the line shown, which looks to the right.

The design consists of an outer border, A, an inner panel, B, with a large central ornament, C, in the form of a bush with leaves D and flowers E. This central panel also contains small ornamental figures F, composed of a stem, leaves, and a piece of fruit. (See illustration.)

The design also consists of two end panels,

G, connected above and below the middle panel, B, by the narrow panels H H'. These end panels are ornamented by the representation of a lion rampant with a shield protecting its side, the rest of each panel being ornamented with scroll-work and oak-leaves, as shown, the upper and lower panels, H H', containing similar scrolls and leaves and rosettes I.

The leading features of my design are the outer border, A, middle panel, B, and end panels, G, and top and bottom panels, H H', the end and top and bottom panels being ornamented with scroll-work and leaves, and each end panel containing a lion rampant partially covered by a shield.

What I claim as new is—

The design for a rug, substantially as shown and described.

ADOLPH PETZOLD.

Witnesses:

GEORGE E. BUCKLEY,
R. J. POMEROY.